ABSTRACT OF THE DISCLOSURE

Anti-glaucoma compositions containing, in an ophthalmic vehicle, 10,11-dihydro-5-(3-methylaminopropyl)-5,10-epoxy-11-hydroxy-5H-dibenzo[a,d]cycloheptene or 10,11-dihydro-5-(3-dimethylaminopropyl)-5,10-epoxy-5H-dibenzo[a,d]cycloheptene-11-hydroxy-imino (or non-toxic addition salts thereof), either singly or in combination with a sympathomimetic amine, as well as methods of treatment.

The present invention relates to topical ophthalmic compositions useful in the treatment of glaucoma. More particularly, this invention relates to anti-glaucoma agents which effectively lower intraocular pressure and to methods for the preparation and administration of such compositions.

Present therapeutic methods for the treatment of glaucoma predominantly involve the use of miotics, carbonic anhydrase inhibitors and surgery. Of these methods the most widely employed for glaucoma therapy is the topical use of miotics, pilocarpine being the most usually employed miotic. This drug generally requires an undesirable frequency of instillation, generally around the clock. Furthermore, tolerance to the drug, requiring increasingly stronger solutions, often up to the highest dosage level usable, and tachyphylaxis are not uncommon disadvantages. Carbonic anhydrase inhibitors are generally not employed as a sole therapeutic measure, but mainly are used concomitantly with miotics in the treatment of chronic glaucoma or preparatory to surgery. Surgery is usually reserved for those cases of chronic glaucoma that do not respond to drug therapy or for the treatment of the somewhat uncommon acute congestive glaucoma. To complete the picture of presently available methods for the treatment of glaucoma, one should mention the anti-cholinesterases. These topical preparations are longer lasting therapeutically than pilocarpine, but unfortunately, produce intense miosis, occasional iris cysts and have been associated with parasympathomimetic systemic effects. Lastly, it can be mentioned that miotics produce a miosis which is generally annoying to the patient because of interference with vision. It, therefore, is quite obvious that there is an outstanding need for new therapeutic agents which can be employed in the treatment of glaucoma and which avoid some or all of the disadvantages of the presently available measures.

It is, therefore, a significant purpose of this invention to provide such novel anti-glaucoma compositions. A further object is to topically administer such compositions to the eye in a dosage form that will significantly lower intraocular pressure while achieving the pupillary goals of a submaximally dilated and mobile pupil, retaining sensitivity to stimulation by light. These and other objects of this invention appear more fully hereinafter.

2

The topical anti-glaucoma compositions of this invention contain one of the following compounds as novel intraocular hypotensive agents:

10,11-dihydro-5-(3-methylaminopropyl)-5,10-epoxy-11-hydroxy-5H-dibenzo[a,d]cycloheptene

10,11-dihydro-5-(3-dimethylaminopropyl)-5,10-epoxy-5H-dibenzo[a,d]cycloheptene-11-hydroxy-imino

in a conventional topical ophthalmic vehicle and in an effective dosage range which upon ocular introduction will lower intraocular pressure. Although the above formulae show the free base, it is to be understood that the non-toxic acid addition salts, such as hydrochloride or hydrogenmaleate, are equivalent for the purposes of this invention.

Although compositions of this invention wherein the novel hypotensive agents form the only active ingredient effectively lower intraocular tension, for some purposes it may be desirable to combine treatment with exogenous sympathomimetic amines. In one embodiment the sympathomimetic amine can be administered with the intraocular hypotensive agent of this invention in a single vehicle in dosages which effectively lower intraocular pressure. Exemplary of such sympathomimetic amines are epinephrine, norepinephrine and isoproterenol. In another embodiment the sympathomimetic amine can be administered following instillation of the novel hypotensive agent of this invention.

The compositions of this invention are administered topically to the eye, either in the form of ophthalmic solutions, or as ophthalmic ointments. Formulations are herein expressed as percent weight by volume and generally the dosages for the intraocular hypotensive agent fall within the range of 0.01 to 0.02 percent. Higher dosages, as for example, up to about 0.2 percent, or lower dosages can be employed, provided the dose is effective in lowering intraocular pressure, is non-irritating and achieves the desired pupillary goals previously set forth.

The procedure for the preparation of the compounds of claim 1 as set forth in U.S. application Ser. No. 481,908, filed Aug. 23, 1965. The sympathomimetic amines, epinephrine and norepinephrine as well as isoproterenol are well known in the art and their properties and method of preparation can be found in standard references as, for example, the Merck Index, 7th edition (1960).

The compositions of this invention are incorporated into a sterile ophthalmic vehicle. Such vehicles are well known in the art and are fully described in such standard reference works as Remington's Pharmaceutical Sciences, Martin and Cook, Mack Publishing Co., Easton, 13th

edition (1965). The following is a suitable example. (The percentages in the following examples refer to a percent weight by volume.)

Sterile vehicle:

8-hydroxyquinolone sulfate	percent	0.01	5
Sodium bisulfite	do	0.3	
Phenylmercuric acetate	do	0.002	
Sodium hydroxide or hydrochloric acid to pH		3.5-6	
Water, q.s. ad.			10

In the foregoing composition the 8-hydroxyquinolone and the sodium bisulfite act as anti-oxidants and can vary tenfold (the former up to about 0.1% and the latter down to about 0.03%). In addition to these specific anti-oxidants, any ophthalmic anti-oxidant can be employed. These are more fully described in Remington (supra).

Phenyl mercuric acetate is employed as a preservative. Any preservative suitable for ophthalmic formulation such as those described in Remington (supra) can be employed.

Although the pH of the foregoing sterile vehicle is adjusted using base or acid it should be recognized that standard buffering agents such as those described in Remington (supra) or in the Merck Index, volume 7 (1960), so long as these buffering agents are suitable for ophthalmic formulation, can be utilized. Thus a pH range from about 3.5-8 can be employed, although pH within the physiological range is preferred. When employing a buffered system it is preferred to utilize a pH of about 6.0 to about 8. With a buffered system pH is conventionally adjusted by adjusting the concentration and at the time altering the ratio of the buffered tonicity so as to maintain an isotonic solution. Although buffers can be used at varying pH, when pH is less than 6.0, sodium hydroxide or hydrochloric acid can conveniently be employed to adjust the pH. When using a buffered system it is preferred to adjust the range to that of the physiological pH range of about 6 to 7.5 or 8. U.S. Patent 3,149,035 sets forth suitable sterile vehicles for use, especially when a catechol amine, such as epinephrine, is employed in the compositions of this invention.

The following examples demonstrate various formulations of the anti-glaucoma compositions of this invention:

EXAMPLE I

	Percent	45
10,11 - dihydro - 5-(3-dimethylaminopropyl)-5,10-epoxy - 5H - dibenzo[a,d]cycloheptene - 11-hydroxy-imino hydrogen maleate	0.02	
Oxine sulfate	0.01	50
Sodium bisulfite	0.3	
Boric acid	0.8	
Sodium borate	0.6	
Phenylmercuric acetate	0.002	
Water, q.s. ad.		55

EXAMPLE II

	Percent	
Trans 10,11 - dihydro-5-(3-methylaminopropyl)-5,10-epoxy-11-hydroxy-5H-dibenzo[a,d]cycloheptene hydrogen maleate	0.02	60
Oxine sulfate	0.01	
Sodium bisulfite	0.3	
Boric acid	0.8	
Sodium borate	0.6	
Phenylmercuric acetate	0.002	
Water, q.s. ad.		65

EXAMPLE III

	Percent
(1) Epinephrine	0.1
10,11 - dihydro - 5-(3-dimethylaminopropyl)-5,10-epoxy - 5H - dibenzo[a,d]cycloheptene - 11-hydroxy-imino hydrogen maleate	0.02
Boric acid	0.8
Sodium borate	0.6
Oxine sulfate	0.01
Phenylmercuric acetate	0.002
Sodium bisulfite	0.3
Water, q.s. ad.	

15

EXAMPLE IV

	Percent
(1) Epinephrine	0.1
Trans 10,11 - dihydro - 5-(3-methylamino-propyl)-5,10 - epoxy - 11 - hydroxy - 5H-dibenzo[a,d]cycloheptene hydrogen maleate	0.02

45

The compositions of this invention can also be administered as ophthalmic ointments. These are compounded, for example, by mixing finely milled powdered ingredients with a small amount of white petrolatum and levigating or otherwise mixing until a uniform distribution is achieved. The balance of white petrolatum is added by geometric addition until the desired dosage form is made.

I claim:

1. An anti-glaucoma topical ophthalmic composition comprising a topical ophthalmic vehicle and 0.01 to 0.2% of a member selected from the group consisting of 10,11-dihydro - 5 - (3-dimethylaminopropyl)-5,10-epoxy-5H-dibenzo[a,d]cycloheptene-11-hydroxy-imino, trans 10,11-dihydro - 5 - (3-dimethylaminopropyl)-5,10-epoxy-11-hydroxy-5H-dibenzo[a,d]cycloheptene and a non-toxic acid addition salt thereof.

2. A method for lowering intraocular pressure which comprises applying topically to the eye an effective amount of a composition comprising a topical ophthalmic vehicle and 0.01 to 0.2% of a member selected from the group consisting of 10,11 - dihydro-5-(3-dimethylaminopropyl)-5,10 - epoxy - 5H-dibenzo[a,d]cycloheptene-11-hydroxy-imino, trans 10,11 - dihydro-5-(3-dimethylaminopropyl)-5,10-epoxy-11-hydroxy-5H-dibenzo[a,d]cycloheptene and a non-toxic acid addition salt thereof.

UNITED STATES PATENT OFFICE
CERTIFICATE OF CORRECTION

Patent No. 3,467,756

Dated September 16, 1969

Inventor(s) Clement A. Stone

It is certified that error appears in the above-identified patent and that said Letters Patent are hereby corrected as shown below:

Column 1 line 16 after "epoxy" insert -- 11-hydroxyimino -- line 17, delete "11-hydroxyimino". Column 2 lines 4-11, structural formula should read:

Column 2 lines 14-22, structural formula should read:

Column 2, name following structural formula II, insert after "epoxy" -- 11-hydroxyimino -- and delete "11-hydroxyimino" after "cycloheptene". Column 3 line 47 after "epoxy" insert -- 11-hydroxyimino --; lines 47 and 48, delete "11-hydroxyimino". Column 4 line 5 after "epoxy" insert -- 11-hydroxyimino --; lines 5 and 6, delete "11-hydroxyimino"; line 41 after "epoxy" insert -- 11-hydroxyimino --; line 42 after "cycloheptene" delete "11-hydroxyimino"; line 52 after "epoxy" insert -- 11-hydroxyimino --; lines 52 and 53 after "cycloheptene" delete "11-hydroxyimino".
